AUTOMATIC WASHING MACHINE

Henry J. Rand, Bratenahl, Ohio, assignor to H. J. Rand Washing Machine Corp., New York, N. Y., a corporation of Delaware

Application January 31, 1948, Serial No. 5,619

17 Claims. (Cl. 68—12)

1

This invention relates to improvements in a washing machine and more particularly to a novel automatic type machine which requires nothing from the operator except to place the dirty clothes in the machine and remove the clean damp clothes from the machine.

An object of the present invention is to provide an automatic washing machine of the type which utilizes a closed flexible bag for holding the clothes during a washing operation and for squeezing the liquid out of the clothes at the end of the washing operation.

Another object of the present invention is to provide in a washing machine using the flexible bag as a container for the clothes and an agitator within the bag for the washing operation, the automatic sequential operations of (1) filling the bag with liquid, (2) agitating the clothes for washing, (3) withdrawing the water and air from the interior of the bag to cause the bag to collapse against the clothes to squeeze the water out of them, (4) to refill the tube with rinse water, (5) to agitate the clothes in the rinse water, (6) to withdraw the rinse water and air from the bag to cause the bag to collapse against the clothes, to repeat the rinsing operation if desired, and finally to terminate the operation.

Another object of the present invention is to use a clock for timing the washing operation but to cut out the clock until the tub has filled with liquid to a predetermined level.

Still another object of the invention is to cut out the clock for timing the drying operation until a predetermined vacuum has been created within the bag.

Other modifications of the invention include the use of the aspirator in one form of the device for withdrawing the water and air from within the flexible container and the use of an electrically operated pump for this purpose in a modified form of the apparatus. In the latter case, a novel connection is provided for using a single electric motor for oscillating the agitator when the motor runs in one direction and for rotating the pump when the motor runs in the opposite direction. In this latter case, automatic control means is provided for reversing the direction of motor rotation in connection with the other automatic operations outlined above.

Another object of the present invention is to provide an aspirator or ejector in communication with the interior of the flexible bag of a machine of the type described in the preceding paragraph together with suitable means for trapping liquid in the aspirator so as to cause it to flow into the

2

bag for filling the same and later using the aspirator in the usual manner to create a suction in the bag to discharge the liquid contents thereof.

My invention also contemplates the use of suitable electric circuits for producing an entirely automatic operation of the washing, rinsing and drying cycle, the use of a pressure switch for stopping the flow of liquid into the bag when it is sufficiently filled, the use of a switch responsive to partial vacuum within the bag for timing a drying operation if desired, the use of suitable valving arrangements for supplying liquid of the desired temperature to the bag for washing or rinsing clothes, and preferably, the use of an unheated liquid for operation of the aspirator during a drying cycle.

Other objects and advantages of the present invention will appear from the accompanying drawings and description and the essential features thereof will be set forth in the appended claims.

In the drawings,

Fig. 1 is a drawing somewhat schematic showing a type of washing machine suitable for my purpose together with a suitable aspirator, valves, vacuum operated switch, and clock operated switches adapted to carry out my invention;

Figs. 2, 3, 4 and 5 are electrical diagrams illustrating various portions of the automatic washing, rinsing and drying cycle.

Fig. 6 shows diagrammatically another form of my invention utilizing an electrically operated motor for oscillating the agitator and for rotating a pump; while

Figs. 7, 8, and 9 are electrical diagrams illustrating various portions of the automatic washing, rinsing, and drying cycle using the device of Fig. 6.

In Fig. 1, I have shown at 10 a type of washing machine adapted for the carrying out of the present invention. This machine embodies some of the principles set forth in my copending application Serial Number 682,322, filed July 9, 1946, issued June 7, 1949, as Patent No. 2,472,682. The

upper portion of the machine provides an air- and liquid-tight flexible bag 11 suitably supported to hold the clothes during a washing operation. In the present instance, this support comprises a tub 12 open at the top and supported on a base 13. The bag 11 has a resilient bead 11a extending around the top thereof by means of which the bag is snapped on to the upper rim of the tub. A cover 14 is adapted to close the top of the bag and tub and is provided with

55 an annular peripheral sealing ring 15 which

engages the bead 11a when the cover is the position shown in Fig. 1. This provides a sealed closure for the normally open mouth of the bag 11. Within the base is a rigid frame 16 on which is mounted a motor 17 which is connected through reduction gearing in the housing 18 to a shaft 19 which carries at its upper end an agitator 20 having a plurality of vanes for the agitation of the clothes during the washing operation in a well known manner. The housing 18 may contain both reduction gearing and mechanism for oscillating the agitator first in one direction and then in the opposite direction in a known manner. Suitable construction is provided where the shaft 19 enters the central portion of the tub and bag to seal the same against leakage. One such form of construction is shown in my above-mentioned copending application. An opening is provided at 21 leading through the bottom of the tub and bag to communicate with the interior of the bag. Openings 29a in the agitator provide ready means for liquid to escape from the interior of the bag to the opening 21. A conduit 22 leads from the opening 21 to an aspirator or ejector 23 of known type. The aspirator has an inlet 23a where a jet of liquid is directed toward a Venturi throat 23b, this liquid later passing through the outlet 23c. A connection 23d is provided in that portion of the aspirator body where a vacuum is created when liquid is flowing through the Venturi throat and the outlet 23c. The conduit 22 connects with the opening 23d.

Preferably, when water is used for washing, a plurality of valves is provided ahead of the inlet 23a for the supply of hot, cold or mixed water to the aspirator. As shown diagrammatically in Fig. 1, a hot water line is connected at 24 and a cold water line at 25. A valve 26 controls the supply of hot water under pressure to the inlet 23a. A valve 27 controls the supply of cold water under pressure to the inlet 23a. Valve 28 controls communication between both the hot and cold water lines and line 29 leading to the inlet 23a. The valve 28 is of known type having controlled jets for both hot and cold water so that a mixing of the two in predetermined ratio is provided giving warm water flow through the conduit 29. The outlet of liquid from the aspirator is controlled by valve 30. All of the valves 26, 27, 28 and 30 are of the self-closing type and preferably utilize the water pressure to hold them closed.

Means is provided for opening each of the above-mentioned valves when desired. The means here shown comprises a suitable solenoid for each of the valves and these solenoids have been designated 26a, 27a, 28a and 30a respectively.

Means is provided for timing the automatic operation of the machine. The means here shown is a time switch 31 which for illustrative purposes is exactly like that shown in United States Patent No. 2,313,064 granted March 9, 1943, to Harry C. Hall. This device is operated by a clock motor 32 and an operating knob 33. The electrical connections are not shown in Fig. 1, but are diagrammatically shown in Figs. 2, 3 and 4.

A pressure switch is provided for the automatic termination of the filling of the bag with liquid. This switch indicated at 34 forms the subject matter of my copending application Serial Number 5,620, filed January 31, 1948. It is sufficient to state here that a large curved

plate 35 underlies a portion of the bottom of bag 11 so as to push downwardly on a stem 36 which operates certain contacts within the switch 34 as will be later described. The valve stem 5 is normally urged upwardly by spring means.

If necessary or desirable, a vacuum operated switch 37 is provided for control of the drying operation. As shown somewhat diagrammatically in Fig. 1, a housing 38 communicates through conduit 39 with conduit 22. A flexible diaphragm 40 is suitably supported in the housing 38 and is connected by a stem 41 with the switch 37. A spring 42 normally urges the switch toward open position. Upon creation of sufficient suction in conduits 22 and 39 and in housing 38 the diaphragm 40 is acted upon by the suction to overcome the spring 42 and close the switch 37.

Referring now to Figs. 2 to 5 inclusive, I have shown diagrammatically how these parts are connected into an electric circuit for automatic operation. A source of electric current is indicated at L1, L2. A water selector switch is shown at 43 having a switch blade 44 which may engage contact 45 to energize line 46 which includes the solenoid 26a or it may be moved to the contact 47 which energizes line 48 which includes the solenoid 28a. This enables the operator to select either hot or warm water for the washing operation. The switch 51 is in the device 31 and is closed by the knob 33 when a proper washing time has been selected and the knob 33 is moved axially to start an automatic cycle. This is the master switch. The switches 52, 53 and 54 are cam operated switches in the device 31 and are operated by the clock motor 32 as taught in the above-mentioned Hall patent. The contact 52a of switch 52 is connected by line 55 to the blade 34a of switch 34. The contact 53a of switch 53 is connected by line 56 with switch blade 44. The contact 53b of switch 53 is connected by line 57 to line 48. The contact 54a of switch 54 is connected by line 58 to the blade 34b of switch 34. The contact 54b of switch 54 is connected by line 59 through solenoid 30a to the line L1. Line 60 connects solenoid 27a in parallel with the solenoid 30a. From the switch blade 34a, contact 34c, in the raised position of the blade, is connected by line 61 to switch 53. Contact 34d engaged in the lowered position of the switch blade is connected through line 62 and 63 to energize motor 17. Switch blade 34b in its lowered position engages contact 34e which is connected through lines 64 and 65 to energize the clock motor 32. The vacuum switch 37 is connected by line 66 between lines 59 and 64.

The automatic operation of my improved machine will now be described. The operator first turns the knob 33 to select a desired period of washing time and then moves the knob axially which closes the switch 51. This operation is inherent in the device shown in the above-mentioned Hall patent. At this point, the switches 52, 53 and 54 (as shown in Fig. 2) are held in engagement with contacts 52a, 53a and 54a respectively by cams in the device 31. The pressure switch operating stem 36 and cap 35 are in their uppermost position if the bag is empty. The switch blade 34a engages contact 34c and so completes a circuit for filling the bag 11 with washing liquid through switch 51, line 67, switch 52, line 55, switch 34a, line 61, switch 53, line 56, switch 54, contact 45 and line 46 to L1 to energize the solenoid 26a which will open the hot water control valve 26 as previously described. Obviously, if the switch 44 were in engagement

with the contact 47 the circuit would be completed through line 48 and solenoid 28a which controls the mixing valve 28 to supply warm water to the bag. The operator manually selects the desired position of switch 44. Since all of the valves have been described as self-closing, the valve 30 controlling discharge of water from the aspirator 23 is closed at this time and the water is forced out of the aspirator at the opening 23d, through conduit 22 and opening 21 to the interior of the bag 11. When the water level reaches the desired height in the bag 11 the pressure switch operator 35 is depressed, against its spring bias, so as to move switch blade 34a against contact 34d. This deenergizes the solenoid 26a so that the flow of washing liquid to the bag ceases. At the same time, a circuit is completed through line 62, motor 17 and line 63 to cause the agitator 20 to start operating. It is assumed that the dirty clothes and necessary soap have been added to the tub. The switch actuator 35 also carries switch blade 34b downwardly to engage contact 34e. This completes a circuit through switch 51, lines 67 and 68, switch 54, line 58, switch 34b, line 64, clock motor 32 and line 65 to L1. This starts the clock motor 32 so as to time the washing operation.

At the end of the predetermined time period for washing, the device 31 moves switches 52, 53 and 54 to the positions shown in Fig. 3. Switch 54 is in engagement with contact 54b whereas the agitator motor 17 and the clock motor 32 have been deenergized. The switch 54 then completes a circuit through switch 51, lines 67 and 68, contact 54b, line 59, and line 60 in parallel therewith, back to L1. This energizes solenoids 27a and 30a. Referring back to Fig. 1, it will be seen that this opens the cold water valve 27 and the exhaust or discharge valve 30. Cold water then passes through the aspirator 23 creating a suction in conduit 22 so that the liquid contents of bag 11 are discharged. Following this the air and vapors are removed from within the bag causing the same to move inwardly to the position shown in broken lines in Fig. 1 so that the bag presses tightly against the bundle of clothes in the center of the tub. Atmospheric pressure entering through openings 12a in the tub press the bag inwardly as a partial vacuum is created within it. The cone portion 14a of the cover forces the bag downwardly against the clothes. As the water leaves the bag the switch operator 35 rises, moving the switch blades 34a and 34b to the broken line positions of Fig. 3 but without completing any circuits. The clock motor 32 might be started immediately upon the evacuation of water from the bag 11, but I prefer to start the clock motor, so as to time the drying operation, after a partial vacuum has been created within the bag 11. To this end, I have provided the vacuum switch 37 previously described. Referring back to Fig. 3, the switch 37 is normally open, as described, until a partial vacuum is created in the housing 38 sufficient to overcome the spring 42. Switch 37 then moves to the broken line position as shown in Fig. 3 and completes a circuit through lines 59, 66, 64 and 65 to energize the clock motor 32 for the timing of the drying operation.

When the device 31 has timed the drying operation, the cams of the device will move the switches 52, 53 and 54 to the position shown in Fig. 4. These positions are the same as shown in Fig. 2 except that switch 53 is now in its downward position engaging contact 53b and com-

pleting a circuit through lines 57 and 48 so as to energize the solenoid 28a independently of switch 44. The reason for this is to supply warm water for rinsing whereas the operator has a choice of hot or warm water for washing. As more fully described in connection with Fig. 2, the rinse water now runs into the bag 11 until the switch blades 34a and 34b are carried downwardly to the broken line positions of Fig. 4. This starts motors 17 and 32 so as to agitate the clothes in the rinse water and to time the same by the device 31. When the clock motor 32 has properly timed the rinsing operation, the device 31 moves the switches 52, 53 and 54 to the position of Fig. 3 for another drying operation. This rinsing and drying may be repeated by the device 31 if desired, after which the switches 52, 53 and 54 are moved to the position shown in Fig. 5 whereupon all operations stop.

20 The operator may then turn the knob 69 on top of the cover 14 to open a valve 70 to permit the entrance of air to the interior of the bag 11 so as to reduce the vacuum permitting the removal of the cover 14. The washed and dried clothes are then removed from the tub and it is ready for another operation.

25 It will be noted from the above that nothing is required of the operator except to place the dirty clothes and a suitable soap or detergent within the bag 11 and properly position the cover 14. After manipulation of the knob 33 to set the desired washing time and close the switch 51, nothing else is required of the operator until the washing and drying is completed. The device is thus completely automatic.

30 In the form of my device shown in Fig. 6, the bag 11, the tub 12, the base 13, the cover 14, the shaft 19, the agitator 20 with its openings 20a and the opening into the interior of the container at 21 are all similar to those shown and described in connection with Fig. 1 and carry out the identical functions there described. The clock timer 31 with its motor 32 and knob 33 are like those shown in Fig. 1. The pressure switch 34 is like the same device in Fig. 1. One of the differences in Fig. 6 is the provision of an electric motor 71 having automatic clutch connections when the motor is operating in one direction for acting through gearing 72 to oscillate the shaft 19 and to cause the agitator to produce a washing operation inside the container. In the opposite direction of rotation of motor 71 it automatically declutches the first named drive and automatically connects a second drive through a pulley connection at 73 with a pump 74 of the rotary vane type for withdrawing the water and air from the bag 11 through conduits 75 and 76. These automatic clutching and declutching devices are fully described and claimed in my copending application, Serial Number 5,621, filed January 31, 1948, now abandoned.

35 Means is provided for filling the bag 11 with water from tap connections, the hot connection being shown at 77 and the cold connection at 78. The flow of hot water is controlled by valve 79 and the flow of cold water is controlled by valve 80. These valves are self-closing and are opened by the solenoids 79a and 80a respectively. The flow of fresh water to the washing machine is through conduits 81 and 16.

40 If necessary or desirable to break the vacuum inside the container automatically, still another connection is indicated at 82 controlled by a valve 83. This valve is self-opening and is main-

tained normally in a closed condition by the energization of its controlling solenoid 83a.

In the device of Fig. 6, the operator first places the clothes and soap within the flexible bag 11 and then operates the clock knob 33 to select the proper washing period and pushes the operating knob endwise which closes the master switch 91 of Fig. 7. The selector switch 84 has been moved to one of its two positions to select either hot or warm water for the washing operation. With the parts in the position of Fig. 7, the automatic operation proceeds as follows. The closing of master switch 91 completes a circuit through switch 92 line 89, pressure switch 34 in its uppermost position, line 90, switch 93, contact 83a, line 91, selector switch 84 and line 85 through the hot water solenoid 79a if the hot water has been selected as shown in Fig. 7. The container 11 then fills with hot water up to a predetermined level which is selected by the setting of the pressure switch. When a sufficient column of water builds up above the switch the blade will be depressed to the broken line position of Fig. 7 which then completes a circuit through contact 88, line 99, and clock motor 32 to start the clock for timing the washing operation. A second circuit is also completed through lines 100 and 101, switch blade 94, lines 102 and 103, and the running winding of motor 71. At the same time a circuit is completed through line 104, switch 95, contact 95a, line 105, the reversing winding R of motor 71, line 106, contact 96a, switch 96, and line 108, to operate motor 71 in the direction which causes the agitator 20 to oscillate. This provides a washing operation for the period of time preselected on the clock mechanism at the end of which time the clock automatically moves the switches for one minute to a position not shown but wherein switches 94, 95 and 96 are in neutral position. This permits the motor 71 to come to a stop and de-energizes the motor winding R. After this the clock moves the switches to the position shown in Fig. 8.

For the drying cycle, a circuit is completed through switch 92, contact 92b, lines 100 and 99, and clock motor 32 to time the drying operation. At the same time another circuit is completed through switch 92, line 101, switch 94, lines 102 and 103, and the running winding of motor 71. At the same time a circuit is completed through lines 102 and 104, switch 95, lines 109 and 106, motor winding R, lines 105 and 107, through switch 96 and line 108 to complete the energization of the motor reversing winding R to cause the motor 71 to operate in a direction which automatically rotates the pump 14. The water and air is then withdrawn from the flexible container 11 until it moves into the dot-dash position of Fig. 6 to squeeze the water out of the clothes. During this operation as the water leaves the tub the switch 34 moves from its full line position of Fig. 8 to its broken line position but without closing any circuits immediately.

At the end of the drying operation, the clock mechanism moves the switches to the full line position of Fig. 9 for a rinsing operation. The clock mechanism holds the switch 94 in the full line position of Fig. 9 for about a minute to permit the motor 71 to cease its rotation and to de-energize the winding R of this motor. The switch 94 is then moved to its broken line position of Fig. 9 and it will be seen that the switches are then in a position very similar to Fig. 7,

except that now the switch 93 engages the contact 93b to close a circuit through lines 98 and 86 to energize the solenoid 80a irrespective of the setting of the selector switch 84. This is for the purpose of rinsing with warm water regardless of the temperature of water selected for washing through the switch 84. The container now fills with rinse water in exactly the same manner as it filled with fresh water in the case described in connection with Fig. 7 until the pressure switch 34 moves to the broken line position of Fig. 9. When the switch 34 drops to its broken line position of Fig. 9 it completes a circuit through contact 88, lines 100 and 101, switch 94 in its broken line position, and lines 102 and 103 through the running winding of motor 71. At the same time, it completes a circuit through lines 102 and 104, switch 95, line 105, motor winding R, line 106, switch 96, and line 108 to operate motor 71 in a direction to oscillate the agitator during the rinsing operation. This rinsing operation is timed by the clock motor 32, and at the end of a predetermined period the switches are returned to the position of Fig. 8 for a drying operation. This rinsing and drying may be repeated if desired and at the close of the final drying operation the switches are always turned to a neutral position and the machine stops. The operator may then manipulate the knob 69 to open the valve 78 and break the vacuum within the container. After this she removes the cover 14 and takes out the clean laundry.

If desired, as mentioned previously, means may be provided in line 82 and valve 83 for automatically breaking the vacuum at the close of each drying operation if necessary or desirable. To this end, an additional switch 110 is provided which is normally closed during the operations above described and completes the circuit through line 111, solenoid 83a and line 112 to hold valve 83 closed. At the end of a drying operation, the clock mechanism may be set to move the switch 110 to the broken line position of Fig. 8. This breaks the circuit through the solenoid 83a and permits valve 83 to open because of its normal bias. This will admit air from the atmosphere through lines 82 and 78 to the interior of the flexible bag container 11 so as to break the vacuum within the bag.

From the foregoing it will be understood that the timer operation is not continuous—the timer operates only through certain portions of the entire cycle. More specifically, the timer is not in operation during that portion of the cycle when the rubber bag is being filled with either the initial wash water or subsequent rinse water. In each of these instances the circuit to the timer is open and the timer motor is stopped, until the pressure switch is in the position shown, for instance, in Figure 3, that position being assumed as a result of pressure of fluid within the bag. When in this position, as heretofore explained, the circuit to the timer is completed. One reason for de-energizing the timer during the various filling cycles is that the machine will then accommodate various water pressures. Obviously, when the machine is installed where the water pressure is comparatively low, the filling period will take a relatively lengthy time; whereas in an area of high water pressure the filling time will be of comparatively short duration. In either event these periods will vary and the variation will be accounted for by the inactivity of the timer during the filling stages. Thus, regardless

of such variations in water pressure, filling to a standard and predetermined level before subsequent operations are performed is assured.

It is also to be observed that provision has been made for stopping the operation of the timer during the drying stage until a substantial vacuum has been obtained within the rubber bag through the extraction of a considerable quantity of water and air therefrom. The means for accomplishing this end comprise a vacuum responsive element 38 connected by a suitable switch which controls the actuation of the timer. Said responsive element can be utilized with either modification of this invention, i. e. with the aspirator means or the vacuum pump means. The purpose of ceasing operation of the timer during this period of the cycle is similar to that set forth above: Either the aspirator or the pump will be subject, to a certain extent, as far as rapidity of operation is concerned, to variations of pressure. Such pressure variations may cause the vacuum operation to be prolonged, and to assure a near perfect vacuum, the timer does not commence to operate until, as stated, a considerable portion of water and air are initially removed.

It will be noted that within the form of my device shown in Figs. 6 to 9, the operation is fully automatic as in the first described form and all the operator need do is to place the clothes and soap within the flexible bag container and then put the cover 14 in place, after which the operation is fully automatic until she removes the clean and wet-dry clothes from the container at the end of the operation.

What I claim is:

1. In a washing machine comprising a flexible bag having a closed bottom and side walls and open at the top and comprising means for closing the top and comprising a clothes agitator within the bag, the novel combination of a conduit communicating with the interior of said bag, an aspirator having a liquid passageway with an inlet and outlet and a connection communicating with said passageway normally for air suction, said connection providing flow communication to said conduit means providing liquid under pressure to said inlet, and means controlling the opening and closing of said outlet, whereby upon closing said outlet, liquid may flow into said bag and upon opening said outlet, liquid and air may flow out of said bag.

2. In a washing machine comprising a flexible bag having a closed bottom and sidewalls and open at the top and comprising means for closing the top and comprising a clothes agitator within the bag, the novel combination of a conduit communicating with the interior of said bag, an aspirator having a liquid passageway with an inlet and outlet and a connection communicating with said passageway normally for air suction, said connection providing flow communication to said conduit means providing liquid under pressure to said inlet and including a first valve for control thereof, a second valve controlling the opening and closing of said outlet, means for causing opening of said first valve and closing of said second valve to provide liquid flow into said bag, and means responsive to a predetermined liquid level in said bag for causing closing of said first valve.

3. In a washing machine comprising a flexible bag having a closed bottom and sidewalls and open at the top and comprising means for closing the top and comprising a clothes agitator within the bag, the novel combination of a con-

duit communicating with the interior of said bag, an aspirator having a liquid passageway with an inlet and outlet and a connection communicating with said passageway normally for air suction, said connection providing flow communication to said conduit means providing liquid under pressure to said inlet and including a first valve for control thereof, a second valve controlling the opening and closing of said outlet, a clock motor, means for stopping said motor, a time switch actuated by said motor, a device responsive to a partial vacuum in said bag, means including said time switch in closed position for causing opening of said first and second valves to operate said aspirator to evacuate the fluid contents of said bag, and means responsive to said vacuum-responsive device for starting said clock motor, whereby said motor will open said time switch for terminating operation of said aspirator.

4. In a washing machine comprising a flexible bag having a closed bottom and sidewalls and open at the top and comprising means for closing the top and comprising a clothes agitator within the bag, the novel combination of a conduit communicating with the interior of said bag, an aspiration having a liquid passageway with an inlet and outlet, and a connection communicating with said passageway normally for air suction, said connection providing flow communication to said conduit means providing liquid under pressure to said inlet and including a normally closed first valve for control thereof, a first solenoid adapted to open said first valve when energized, a normally closed second valve for controlling said outlet, a second solenoid adapted to open said second valve when energized, a clock motor, a time switch actuated by said motor and having first and second positions, a device responsive to a partial vacuum in said bag, an electrical circuit including said switch in said first position and said first and second solenoids for causing opening of said valves and operation of said aspirator to evacuate the fluid contents of said bag, a second electrical circuit including said time switch in said second position and said clock motor and a switch closable by said vacuum-responsive device, whereby said clock motor starts responsive to a predetermined vacuum in said bag, and said clock motor being adapted to move said time switch out of said one position after a predetermined time to terminate operation of said aspirator.

5. In a washing machine comprising a flexible bag having a closed bottom and sidewalls and open at the top and comprising means for closing the top and comprising a clothes agitator within the bag, the novel combination of a conduit communicating with the interior of said bag, an aspirator having a liquid passageway with an inlet and outlet and a connection communicating with said passageway normally for air suction, said connection providing flow communication to said conduit means providing a wash liquid under pressure to said inlet and including a first valve for control thereof, a second valve controlling the opening and closing of said outlet, means for causing opening of said first valve and closing of said second valve to provide wash liquid flow into said bag, and means responsive to a predetermined liquid level in said bag for causing closing of said first valve and for causing operation of said agitator.

6. In a washing machine comprising a flexible bag having a closed bottom and sidewalls and open

at the top and comprising means for closing the top and comprising a clothes agitator within the bag, the novel combination of a conduit communicating with the interior of said bag, an aspirator having a liquid passageway with an inlet and outlet and a connection communicating with said passageway normally for air suction, said connection providing flow communication to said conduit means providing a wash liquid under pressure to said inlet and including a first valve for control thereof, a second valve controlling the opening and closing of said outlet, means providing aspirating liquid under pressure to said inlet and including a third valve for control thereof, a timing device, means for causing opening of said first valve and closing of said second valve to provide wash liquid flow into said bag, means responsive to a predetermined liquid level in said bag for causing closing of said first valve and for causing operation of said agitator and for causing starting of said timing device, and means responsive to said timing device for causing stoppage of said agitator and for causing opening of said second and third valves whereby to operate said aspirator to evacuate the fluid contents of said bag.

7. The combination of claim 6 including a device responsive to a partial vacuum in said bag, means responsive to said vacuum-responsive device for starting said timing device, and means responsive to said timing device for terminating operation of said aspirator.

8. In a washing machine comprising a flexible bag having a closed bottom and sidewalls and open at the top and comprising means for closing the top and comprising a clothes agitator within the bag, the novel combination of an aspirator communicating with the interior of said bag for creating a partial vacuum therein, a timing device, a device responsive to a partial vacuum in said bag, an operative connection between said devices for starting said timing device responsive to said vacuum-responsive device, and means operated by said timing device for terminating operation of said aspirator.

9. In a washing machine comprising a flexible liquid- and air-tight bag adapted to hold laundry and liquid, means for supplying liquid to the interior of said bag, means for withdrawing liquid and air from said bag to collapse said bag upon said laundry, electrical clock mechanism, switch means responsive to liquid in said bag at a predetermined level said switch means actuating said clock mechanism, means responsive to actuation of said clock mechanism for opening said liquid supplying means, means responsive to said switch means at said predetermined level for closing said liquid-supplying means and for starting said laundry-agitating means, means responsive to said clock mechanism for stopping said laundry-agitating means and for starting said liquid- and air-withdrawing means, and means responsive to said clock mechanism for stopping said liquid- and air-withdrawing means.

10. In a washing machine comprising a flexible liquid- and air-tight bag adapted to hold laundry and liquid, means for supplying liquid to the interior of said bag, means for agitating laundry in said bag, means for withdrawing liquid and air from said bag to collapse said bag upon said laundry, electrical clock mechanism, switch means responsive to liquid in said bag at a predetermined level only, said switch means having bag-empty and bag-full positions, means responsive to

said bag-empty position for stopping said clock mechanism, means responsive to energization of said clock mechanism for opening said liquid-supplying means, means responsive to said switch means in bag-full position for closing said liquid-supplying means and for starting said clock mechanism and said laundry-agitating means, means responsive to said clock mechanism for stopping said laundry-agitating means and for starting said liquid- and air-withdrawing means, means responsive to said clock mechanism for stopping said liquid- and air-withdrawing means, and means thereafter responsive to said clock mechanism for causing open communication between the interior of said bag and atmosphere to release the vacuum within said bag.

11. In a washing machine comprising a flexible liquid and airtight bag having side and bottom walls and adapted to hold laundry and liquid, an agitating means within said bag and a driving motor therefor, a timer mechanism, vacuum creating means in operative relation with said bag for the removal of liquid and air therefrom, an element positioned against the exterior of one of said walls, said element being responsive to fluid pressure within said flexible bag, said element actuating said timer mechanism and said agitating means at a predetermined level of said liquid and stopping said timer on subsequent decrease of pressure within said bag, and means responsive to said vacuum within the bag for again actuating said timer only after fluid and air have been removed therefrom in a predetermined amount.

12. In a washer and extractor of the character described employing a collapsible flexible container, a timing mechanism, a washing element and a driving motor therefor, an electrically actuated water inlet mechanism, the combination therewith of a switch having one contact closed by pressure of a wall of said flexible container when containing liquid, connections from said contact for starting said timing mechanism, the washing element, and the driving motor, a second contact on said switch being closed when said container collapses, said switch spring biased to open said first mentioned contact on closing of said second contact, a switch actuated by said timing mechanism and in series with said electrically actuated water inlet mechanism thereby to condition said water inlet mechanism for actuation on closing of said second contact.

13. In a washer and extractor of the character described employing a container having a flexible wall moveable from an expanded liquid containing position for washing to a collapsed position for extraction, a washing mechanism within said container, a motor for driving said washing mechanism, mechanism for control of washing and extraction operations in sequence comprising a timer and a control switch having a pair of electrical contacts, the first of said contacts being connected to close, and a second contact being connected to open in response to liquid pressure on said container wall corresponding to a predetermined quantity of washing liquid contained therein, said first and second contacts being biased to assume an opposite position, namely, to open and to close respectively, on decrease of pressure in said container corresponding to an empty container or collapse of said flexible wall, and a liquid supply valve, said first contact on closure being connected to control actuation of said washing mechanism through said motor and said timer, and said second contact on closure

being connected to control operation of said liquid supply valve.

14. In a washer and extractor of the character described employing a container having a flexible wall moveable from a liquid containing position for washing to a collapsed position for extraction, a timer for timing the sequence of washing and drying, a water inlet valve, a washing mechanism within said container, a motor for driving said washing mechanism, a switch actuator responsive to pressure of contained liquid against said container wall, a contact controlled by said actuator opened in response to pressure on said wall, and a second contact closed by said pressure, said first contact controlling a circuit through said water inlet valve, and said second contact controlling a circuit through said motor for said washing mechanism and said timer, said second contact being adapted to open during a portion of the period said wall is in collapsed position.

15. In an automatic washer and extractor of the type employing a flexible wall container for containing washing liquid and having means to collapse said container for extraction of liquid therefrom, a washing mechanism within said container, a water inlet valve, a timing mechanism, a manually operable control to open said water inlet valve to flow water into said container, a control responsive to liquid pressure on said flexible liquid container wall connected to close said water inlet valve when said container fills with liquid to a predetermined amount, said control also being responsive to said liquid pressure on said container wall to start said washing mechanism and said timing mechanism.

16. A washing machine comprising a flexible liquid and airtight bag having bottom and side walls and adapted to hold laundry and liquid, a timer mechanism, a laundry agitating means, means to create a substantial vacuum within said bag by withdrawal of liquid and air therefrom, an element positioned against the exterior surface of one of said walls and responsive to the amount of pressure within said bag, and not in contact with said liquid, said element actuating said timer and said agitating means when said bag is filled with liquid to a predetermined level, means for stopping said timer mech-

anism and said agitating means after a predetermined period, and means for again actuating said timer mechanism only after pressure has been reduced a predetermined amount by said vacuum creating means.

17. A mechanism of the character described having a flexible wall container, said container having expanded and collapsed positions, an agitator within said container, a timing mechanism, an electrically actuated inlet valve and a main drive motor for said agitator, including a switch having first and second contacts, said first contact adapted to close on movement of said container to collapsed position and open on movement of said container to expanded position, said second contact being adapted to open on movement of said container to collapsed position and close on movement of said container to expanded position, said first contact having connections to actuate said inlet valve to cause flow of water into said container, said second contact controlling circuits to said timing mechanism and said main drive motor whereby said timing mechanism and main drive motor are started when said second contact is closed, and a third contact actuated by said timing mechanism during a portion only of the cycle thereof for closing the circuit independently of said second contact.

30 HENRY J. RAND.
